UNITED STATES PATENT OFFICE.

JOHN H. ELWARD, OF HUTCHINSON, KANSAS.

CAR-VENTILATOR.

No. 846,098.

Specification of Letters Patent.

Patented March 5, 1907.

Application filed June 14, 1905. Serial No. 265,235.

To all whom it may concern:

Be it known that I, JOHN H. ELWARD, a citizen of the United States, residing at Hutchinson, in the county of Reno and State 5 of Kansas, have invented certain new and useful Improvements in Car-Ventilators, of which the following is a specification, reference being had therein to the accompanying drawing.

10 This invention relates to improvements in car-ventilators, it pertaining particularly to that style of ventilator in which a current of air is drawn into the car by mechanical devices and then distributed within the car, the action of the devices being automatic in 15 nature.

Figure 1 is a view, partly in side elevation and partly in cross-section, of a car provided with a ventilator embodying my improvements. Fig. 2 is a section on the line 22, Fig. 1. Fig. 3 is a side elevation of the ventilating apparatus drawn on a larger scale than Fig. 1.

In the drawings, A represents the car as an 25 entirety. It may be of any well-known style.

B represents as an entirety the ventilating apparatus, which may be arranged at either end, or there may be two of them at opposite ends of the car, if desired. This ventilating 30 apparatus consists of a motor C, an air-pump D, and an air-distributing device E. Preferably the motor for each ventilating device consists of two windmills or wind-wheels arranged at either side of the car in the same 35 vertical transverse plane. These mills are identical in construction, each comprising the bearing-frame 1 and a wind or paddle wheel 2. The bearing-frame 1 is preferably constructed as shown, having the side walls 40 1^a, of sheet metal, arranged at an angle to each other and to the body of the car and rigidly secured to the roof of the car, and the end plates 1^b and 1^c. The end wall 1^b at the inner end of the bearing-frame is secured at 45 either end to the said side walls 1^a and rests at its lower edge upon the roof of the car. The end wall 1^c at the outer end of the frame is secured at its ends to the side walls of the frame and extends from the upper edges of 50 the said side walls to a point somewhat above the roof of the car, so as to leave an open space free between the roof of the car and the under edge of the wall 1^c, through which rain, snow, dirt, or the like may pass off from the 55 interior of the bearing-frame. 4 indicates a crank-shaft mounted in bearings 5 in the

said bearing-frame. The paddles or blades 5 of the windmill are rigidly secured to the said crank-shaft and are preferably arranged as shown, each at right angles to the next adjacent one. The crank-shaft 4 extends inwardly to the central vertical longitudinal plane of the car and has its inner end mounted in the bearing 6, carried by a shaft-hanger 7, suspended from the roof of the car. 60 65

8 indicates the crank at the inner end of the crank-shaft.

The pump D preferably consists of a vertically-arranged cylinder 9, having at its upper end a duct 9', leading through the roof of 70 the car and communicating with the outside air.

10 indicates the pump-plunger arranged within the cylinder and adapted to reciprocate therein, and 10' the plunger-rod. 75

11 is a check-valve arranged in the cylinder between the plunger-head and the port through which the said cylinder 9 may be brought into communication with the outside air. This check-valve 11 may be of any 80 well-known type, it simply serving to admit air to the pump-cylinder on the downward or suction stroke of the plunger therein and to close during the return or forcing stroke of the plunger. 85

12 is a duct leading from the upper end of the cylinder 9 downwardly and opening into the interior of the car. Through this duct 12 the air is forced by the pump-plunger on its upward stroke. 90

13 is a cross-bar secured to the lower end of the plunger-rod, and 14 are connecting-rods connecting the cranks 8 with the ends of the said cross-bar 13.

Immediately beneath the lower end of the 95 air-delivery duct 12 I arrange a cup-shaped distributor 15, into the cavity of which the lower end of the said pipe extends. This cup-like distributor is secured in position by means of braces 15', rigidly secured to the 100 convex surface of the distributor and to the walls of the duct 12. 16 is a duct communicating at its upper end with the interior of the said cup-shaped distributor through the port arranged directly in line with the air-supply duct 12 and communicating at its 105 lower end with the outer air. This pipe 16 is adapted to furnish an outlet for the dust or foreign particles which may be drawn into the pump and forced through the air-duct 110 12. The diameter of the duct 16 is relatively much smaller than the diameter of the air-

duct 12, so that but a small portion of the air passing through the duct 12 can escape through the duct 16, and at the same time the pressure within the duct 16 will remain 5 sufficiently high to insure that all foreign particles will be rapidly carried away.

16^a is a valve or stop-cock in the pipe 16, adapted to permit the cutting off of the passage of air therethrough when desired. The 10 connection between the pipe 16 and the cup-shaped distributor 15 may be through a funnel-shaped port 17, if desired, this funnel-shaped port insuring that all particles of dust and foreign material carried over by the air- 15 duct 12 will be delivered directly to the duct 16.

18 is a valve arranged in the duct 9', extending from the cylinder to the open air and adapted to regulate the amount of air that 20 can be drawn into the pumping-cylinder.

The blades of the coöperating fans at either side of the car may preferably be staggered with relation to each other, as indicated in Fig. 2, so as to insure that one blade of one of 25 the fans will always be in position to oppose the force of the air to which the fan is subjected.

In order to avoid clogging up of the interior of the bearing-standards during snow- 30 storms, I have provided a hood or deflector 19, arranged above and extending over the wind-wheel and having the sloping walls 19' 19^a, which tend to carry off or deflect the snow from the blades or paddles of the wheel, 35 while at the same time their ends are above the tops of the fan-blades, so that they will not in any wise interfere with the currents of air that are to act upon the blades.

20 is a cowl swiveled to the upper end of 40 the duct 9', which leads from the pumping-cylinder to the outside air and having the directing-blade 20', adapted to maintain the said cowl with its mouth at all times directed

away from the currents of air to which the cowl is subjected, so as to insure that the air 45 which is drawn into the pump-cylinder will be as free from dust and the like as possible.

What I claim is—

1. In a car-ventilating apparatus, the combination of an open-ended bearing or supporting-frame having inclined side walls 1^a arranged to be secured to the roof of a car, and end plates 1^b and 1^c, the outer end plate being arranged with its lower edge somewhat above the roof of the car so as to leave an 55 open space for the escape of snow, dirt and the like, a wind-wheel located in the said bearing-frame and air-forcing means connected with and operated by the said wind-wheel, substantially as described. 60

2. In a car-ventilating apparatus, the combination of an open-ended and open-top bearing or supporting frame, the outer end wall thereof having its lower edge above the support to which the frame is secured to permit 65 the escape of snow and like material, a hood 19 over the top of the frame, a wind-wheel 19 mounted in the said bearing-frame, and air-forcing means connected with and operated by the said wind-wheel, substantially as de- 70 scribed.

3. In a car-ventilating apparatus, the combination of a wind-wheel supported on the top of a car, a pump located inside the car and connected with and operated by the 75 wind-wheel, an inlet-pipe leading from the outer air to the pump, a cowl at the end of the inlet-pipe, and distributing-pipes within the car leading from the pump, substantially as described. 80

In testimony whereof I affix my signature in presence of two witnesses.

JOHN H. ELWARD.
